DESIGN FOR A DILUTER FOR LUBRICANTS

Thomas Gallo, Arlington, Va.

Application August 26, 1942, Serial No. 108,039

Term of patent 3½ years

To all whom it may concern:

Be it known that I, Thomas Gallo, an employee of the United States Government, a citizen of the United States, residing at Arlington, Virginia, have invented a new, original, and ornamental Design for a Diluter for Lubricants, of which the following is a specification, reference being had to the accompanying drawing, forming part thereof.

Fig. 1 is a front elevational view of a diluter for lubricants, showing my new design,
Fig. 2 is a side elevational view, and
Fig. 3 is a plan view of same.

I claim:
The ornamental design for a diluter for lubricants, as shown.

THOMAS GALLO.
